W. GRAHAM-BARNETT

DEVICE FOR CURLING AND WAVING THE HAIR

Original Filed Nov. 13, 1925

UNITED STATES PATENT OFFICE.

WILLIAM GRAHAM-BARNETT, OF NEW YORK, N. Y.

DEVICE FOR CURLING AND WAVING THE HAIR.

Application filed November 13, 1925, Serial No. 68,902. Renewed October 23, 1926.

This invention relates to improvements in devices for curling and waving the hair and has for its principal object the provision of a new and improved construction 5 of hair waving device which may be heated, but which is adapted for operation independently of any external source of heat energy.

A further object of this invention is to 10 provide a hair waving or steaming tool which will have therein but separated therefrom a separate steam generating chamber.

Further objects of the invention will be 15 apparent from the specification and drawings in which—

Fig. 1 is an elevational view of my improved device.

Fig. 2 is a sectional view of the device as 20 shown in elevation in Fig. 1.

Fig. 3 is an elevation of the device with the locking means for the hair curler shown in an inoperative position or unlocked.

Fig. 4 is a sectional view along the line 25 4—4 of Fig. 3.

Fig. 5 is a rear view of the device showing the hair curler locked within the 30 chamber.

Fig. 6 is a sectional view of a modified 35 form of the device.

Fig. 7 is a transverse view partly in section of another modification.

10 is the body or outer chamber of my improved hair waving device. 11 is the cover which is attached to the body 10 by 35 a bayonet-slot by means of the pin 25. 12 is a supplemental chamber within the body 10, but not connected therewith, which contains the hair curler itself. The heating means for curling or waving the hair is 40 placed in the chamber of the body 10 outside of the chamber 12. 13 is the stem of the hair curling appliance which may be of any of the well known forms and around which the hair to be curled 14 is wound. 45 The stem 13 is surmounted by a cone-shaped cap 15 which is held within the body of the chamber 12, by a spring as shown and may be detached at will.

In the chamber 12 are slots 16 which act 50 as ducts for the steam evolved in the body of the device. The steam is created within the chamber of the body 10 by the action of drops of water falling on a quicklime or other material which evolves a considerable 55 quantity of heat in reacting with water. This material is shown as 17 and is enclosed

in a protective layer 17 preferably of fibrous or textile material as shown. The source of the water to react with the quicklime or other heat and steam forming element is the 60 reservoir S opening into the tube 18 so that water may be gradually sprayed into the element 17 as desired. The reaction between the water and the material 17 is exothermic, and results in the production of steam which 65 enters the supplemental chamber 12. Since the cover of the main chamber is wholly independent of the cover 19 of the supplemental chamber, and since said covers 11 and 19 have independent fastening means, 70 the layer or pad 17' can be replaced without opening the supplemental chamber. 19 is a cap or cover tightly fitting the opening of the chamber 12 which is locked by means of the hook 20 tightly held in position 75 against the cap 19 by the strap 21 passing through the guides 22. The strap 21 terminates in an eye upon which the locking member 23 is pivoted as is shown in Fig. 1 which shows the cover or cap 19 in locked 80 position, whereas Fig. 3 shows the cap open for removal of the hair curler in the chamber 12. 24 is the eye cooperating with the hook 20 serving to keep the cap 19 in locked 85 position. 27 is the handle of the device preferably made of hard rubber, wood, or other heat insulating material by which the entire device may be freely handled by the operator when the device is in use.

Fig. 6 shows a modification of the device 90 in sectional view containing a chamber or body 10' and a supplementary chamber 12' which is positioned directly in the middle and on top of the chamber 10'. The advantage of this modification is that the body 95 of the chamber 10' is rectangular in cross section.

In Fig. 7 is shown another modification of the device, in that the cap 26', corresponding to the cap 11 in Figs. 1 and 3 is 100 in the modification shown in Fig. 7, and has a tray extension 26 which acts as a holder for the heating element 17.

The operation of the device is as follows:—

The ringlet or hair which is to be waved, is wound around the stem 13, the cap 19 is closed and then water is gradually sprayed upon the quicklime or other heat and steam forming member 17 until a 110 proper degree of heat is induced within the chamber 12. The steam evolved from the

water dripping on the heat element 17, is led through the openings 16 into the chamber 12. By this device only a few moments are required to attain a proper degree of heat within the chamber 12 and as soon as this degree of heat is attained, no further water is supplied to the material 17. An advantage of a device of this character containing a chemical heating element, is that over-heating is readily avoided.

Having fully described my invention, what I claim is:—

1. In a hair waving device, the combination of two connected chambers, one of said chambers being adapted to contain a reacting heat-yielding mass containing water so that steam is generated and enters the other chamber, said other chamber being adapted to have a hair curling device placed therein, said chambers having independent inlets, said chambers having independent closures for said inlets.

2. In a hair waving device, a hollow body divided into a main chamber and another

chamber by a perforated partition, the main chamber being adapted to contain a reacting and heat-yielding mass containing water so that steam is generated and enters the other chamber, said other chamber being adapted to have a hair curling device located therein, said main chamber having an opening at one end of said body and said other chamber having an opening at the other side of said body, each said chamber being provided with an independent closure.

3. In a hair curling or waving device, a main chamber, a supplementary chamber divided therefrom, but connected thereto by steam ducts, a cap for said supplementary chamber and fastening means for said cap on the outside of the main chamber, a separate cover for the main chamber removably held thereon and a tray fastened to said cover, said tray being adapted to hold a heat forming element.

In testimony whereof I affix my signature.
WILLIAM GRAHAM-BARNETT.
